PROCESS FOR HEAT TREATING METALS AND ALLOYS.

Application filed November 21, 1925, Serial No. 70,673, and in Great Britain October 3, 1925.

This invention relates to process for heat treating metals and alloys in linear form composed of a wire, a tape or a plurality of wires, tapes or tapes and wires forming a cable, and hereinafter alluded to under the generic term of "a conductor", and more particularly to the annealing of loaded telegraph and telephone conductors.

It is well known that metals and alloys of metals, such as copper, deteriorate rapidly when heated in air or in the presence of reducing gases, and even small quantities of such gases have a marked effect on their properties, and in order to develop the maximum permeability of the loading material, it is usual to pass the conductor through a tube of refractory material placed inside a suitable furnace to which tube an inert gas, such as nitrogen, is supplied to overcome this difficulty. Further in order that the loaded conductor may be still protected from oxidation after leaving the furnace until it is cool, this tube is generally prolonged, and may be provided with a jacket through which cold water is kept in circulation.

The success of the annealing process is greatly influenced by the distribution and flow of the inert gas within the tube, and the object of this invention is to provide a means whereby this distribution and flow of gas may be such as to produce the best possible result.

In order to describe fully the object of the invention, it must be explained that, while it is necessary to prevent unduly oxidizing the loaded conductor, it is also advisable to retain such oxygen as is already included in the copper since, without this oxygen the copper becomes brittle. But any loaded conductor is liable to have upon each of its component parts, a film of oil, which is an almost unavoidable result of the various processes used in the manufacture. As the temperature of the conductor rises in the furnace tube, this oil is volatilized, and the resulting fumes come into contact with the conductor further in the tube, which is heated to redness, the hydrogen of these fumes will combine with the oxygen in the copper, thus reducing the latter to the brittle state mentioned above.

In order to avoid this, the inert gas is introduced into the tube near the point where the wire leaves the furnace, and enters the

cooling portion of the tube. The effect of this arrangement is that the entering gas divides into two streams, one of which flows through the cooling tube and so out into the atmosphere, and the other flows through the heating tube, and meeting the oily fumes carries them out into the atmosphere at the end where the conductor enters the tube.

This method, however, has the disadvantage that the cold gas, meeting the surface of the conductor where it is still at or above its critical temperature, chills it with undue rapidity.

According to this invention the heating tube, through which the conductor or article to be treated is passed, is supplied with an inert gas at two points, at a substantial distance apart from one another; thus one of the gas inlets may be situated comparatively near to the commencement of the heating zone while a second inlet may be situated comparatively near the end of the heating zone.

The gas may be supplied at these points through a single pipe traversing a considerable length of the furnace before connecting with the heating tube.

The first of said gas inlets may be subdivided into a plurality of inlets and for this purpose a portion of the heating tube adjacent the inlet end may be jacketed and provided with a number of perforations establishing communication with the space inside the jacket, to which gas is supplied, preferably through a pipe entering the side of the jacket opposite the perforations in the heating tube.

A second pipe may also be provided for the supply of gas to the heating tube, corresponding to the second gas inlet. The heating tube may be extended to form a cooling tube which is water-jacketed.

When two pipes are provided for the supply of gas the pressure may be so adjusted that practically all the gas in the annular space inside the jacket, and that passing through the perforations into the heating tube, is discharged into the atmosphere at the inlet end, whereas the gas from the second supply pipe passes mainly along the heating tube in the opposite direction.

It will be seen that the gases are raised to a temperature in the neighbourhood of that of the conductor before coming into contact with it and any traces of oil and grease upon

the object undergoing treatment become volatized and are blown out into the atmosphere, together with any particles of dirt.

The invention is illustrated diagrammatically in Figures 1 and 2 of the accompanying drawings with reference to the annealing of a loaded telegraph or telephone conductor, but it should be understood that the furnace may be modified to meet other requirements.

Referring to Figure 1 of the drawings, 1 is the furnace preferably heated by electrical means, and a suitable length for which may be about 12 feet. In the furnace is a heating tube 2 having two gas inlets 3 and 4 connected to a pipe 5 for the supply of gas. The heating tube is prolonged to form a cooling tube 6 which is provided with a water jacket 7.

In Figure 2 a portion of the heating tube is provided with a jacket 8 having a supply pipe 9 and the second inlet is supplied with gas through a pipe 10.

The first portion of the heating tube is perforated as at 11 so that gas may pass to the interior of the heating tube from the jacket.

In operation the loaded conductor is led into the annealing tube from the left hand side of the furnace 1, and nitrogen is passed through the supply pipe or pipes, the pressure of which may be adjusted as desired.

What we claim is:—

1. A process for heat treating metals and alloys consisting in passing the article to be treated through a heating tube, and in supplying an inert gas to said tube at two points,

so that the gas supplied at one point will flow to the atmosphere at the inlet end of the heating tube and serve to dispel the volatilized matter of distillation, and the gas supplied at the other point will flow to the outlet and serve to prevent oxidation and reduction of the article.

2. A process for heat treating metals and alloys consisting in passing the article to be treated through a heating member, and in supplying an inert gas to said member at two points, the first point being substantially at the beginning of the zone of heating, so that the gas supplied at one point will flow to the atmosphere at the inlet end of the heating member and serve to dispel the volatilized matter of distillation, and the gas supplied at the other point will flow to the outlet and serve to prevent oxidation and reduction of the article.

3. A process for heat treating metals and alloys consisting in passing the article to be treated through a heating tube, and in supplying an inert gas to said tube at two points spaced from each other and from the ends of the heating zone of said tube, the quantity and pressure of gas supplied being controlled so that there is no appreciable flow of gas between the two points.

In testimony that we can claim the foregoing as our invention we have signed our names this 29th day of October 1925.
